(57) **CLAIM**

The ornamental design for an electrode strip, as shown and described.

DESCRIPTION

FIG. 1 is a front elevational view of an electrode strip showing my new design;

FIG. 2 is a bottom perspective view thereof;

FIG. 3 is a rear elevational view thereof;

FIG. 4 is a left side perspective view thereof;

FIG. 5 is a right side perspective view thereof; and,

FIG. 6 is a top perspective view thereof.

The broken line showing of the text and symbols within the circles in FIG. 3 is for environmental purposes only and forms no part of the claimed design.
